UNITED STATES PATENT OFFICE.

HOLDEN RIGBY, OF PATERSON, NEW JERSEY.

SELF-LUBRICATING LEAF-SPRING.

1,288,994.

Specification of Letters Patent. Patented Dec. 24, 1918.

Application filed November 5, 1918. Serial No. 261,253.

To all whom it may concern:

Be it known that I, HOLDEN RIGBY, a citizen of the United States, and a resident of Paterson, in the county of Passaic and State 5 of New Jersey, have invented a new and Improved Self-Lubricating Leaf-Spring, of which the following is a full, clear, and exact description.

The invention relates to leaf springs such 10 as shown and described in the application for Letters Patent of the United States, Serial No. 204,696, filed by me on November 30, 1917.

The object of the invention is to provide 15 a new and improved self lubricating leaf spring more especially designed for use on automobiles and other vehicles and devices and arranged to insure a continuous and effective lubrication of the leaves without 20 requiring attention on the part of the owner and to reduce to a minimum the wear incident to the rubbing of the superimposed leaves one on the other. Another object is to assure a good spring action and re- 25 silency thereby reducing to a minimum cost of up-keep expenses regardless of road conditions also adding to the comfort and pleasure of the occupants of the vehicle. Another object is to permit of manufacturing 30 the leaves from rolled steel stock thereby producing the leaf springs at a comparatively low cost.

With these and other objects in view the invention consists of certain novel features 35 of construction as hereinafter shown and described and then specifically pointed out in the claims.

A practical embodiment of the invention is represented in the accompanying drawings forming a part of this specification, in which similar characters of reference indicate corresponding parts in all the views.

Figure 1 is a plan view of the improved leaf spring in position on an automobile, a 45 portion of the upper leaf being shown broken out;

Fig. 2 is a side elevation of the same with the axle and its casing shown in section;

Fig. 3 is an enlarged cross section of the 50 same on the line 3—3 of Fig. 2;

Fig. 4 is a plan view of the stock from which the leaves are made;

Fig. 5 is a plan view of a portion of one 55 of the leaves with the central bolt in position; and

Fig. 6 is a cross section of the same.

The improved leaf spring 10 illustrated in the drawings is in the form of a semi-elliptical spring, but it is expressly understood that I do not limit myself to this particular 60 type of leaf spring as the improvement described in detail may be applied to quarter-elliptical leaf springs or other types of leaf springs. As shown, the superimposed leaves 11 are fastened by clips 12 to the casing 13 of the axle 14 and the leaves are connected with each other at the middle by a standard bolt 15 having a washer 16 and a nut 17 and which washer 16 rests on the top of the up- 65 permost leaf 11.

Each of the leaves 11 is provided with a flat smooth under surface and each of the leaves except the top one is provided on the top with longitudinally extending passageways 20 and retarding and spreading members 21 in the form of bosses integral with the leaf. The passageways 20 and the bosses 21 are formed during the process of rolling the stock in a suitably constructed mill, and this stock shown in Fig. 4 is 70 cut transversely according to the length of the spring to be made by the spring manufacturer. The passageways 20 are, at least, two in number and are sinuous in shape, 75 as plainly indicated in Figs. 1, 4 and 5, and the retarding and spreading members 21 are arranged in staggered relation and are preferably of almond shape. The upper faces of the retarding and spreading members 21 are flush with the upper face of the corresponding leaf and the passageways 20, and the upper faces of the members 21 are overlaid by the flat smooth face of the next adjacent leaf. It will be noticed that the lubricating oil has its flow through the passageways 20 retarded by the retarding and spreading members 21 and the lubricating 80 oil is spread widthwise by the said members to cause the lubricating oil to lubricate the contacting surfaces of adjacent leaves 11. 85

The grooves 20 are at the middle of each leaf connected with an elongated aperture 22 formed centrally in the leaf and through which aperture extends the standard bolt 15, as indicated in Fig. 5. It will be noticed 90 that the apertures 22 of the several superimposed leaf springs are in register with each other and they form oil wells on opposite sides of the bolts 15 to permit the oil 95 in the said oil wells to readily pass to the 100 105 110

passageways 20 to be distributed practically throughout the length of the leaf spring as well as the width thereof owing to the retardation in the flow of the oil by 5 the members 21 and the rubbing action of the leaves one upon the other thereby causing the distribution of the lubricant between the leaves. It will also be noticed that by the arrangement described the oil is retained 10 in the passageways 20 and hence the spring leaves are not liable to become dry and to rust at their contacting faces.

In order to supply the oil wells formed by the registering apertures 22 with oil use 15 is made of an oil supplying device 30, preferably of the construction more fully shown and described in the application for Letters Patent of the United States above referred to so that further detailed description of 20 the same is not deemed necessary.

Having thus described my invention, I claim as new and desire to secure by Letters Patent:—

1. A leaf spring, comprising a plurality 25 of superimposed leaves, each having one face flat and smooth and having the other face provided with longitudinally extending passageways for a lubricating oil, and integral retarding and spreading means in 30 the passageways to retard the flow of the lubricating oil in the passageways and to spread the lubricating oil widthwise between the contacting faces of adjacent leaves, the said grooves and retarding means being 35 overlaid by the flat smooth face of the next

adjacent leaf, and means supplying said passageways with a lubricating oil.

2. A leaf spring, comprising a plurality of superimposed leaves, each having one face flat and smooth and having the other 40 face provided with longitudinal sunken passageways over which extends the flat smooth face of the next adjacent leaf, the said passageways being at least two in number and of sinuous shape, and retarding and spreading members integral with the leaf and arranged to space the passageways apart, the said retarding and spreading members being 45 flush with the corresponding face of the leaf to provide retarding means for retarding the flow of the lubricating oil and spreading the same widthwise of the leaf.

3. A leaf spring, comprising a plurality of superimposed leaves, each having one face flat and smooth and having the other 50 face provided with longitudinal sunken passageways over which extends the flat smooth face of the next adjacent leaf, the said passageways being at least two in number and of sinuous shape, and retarding and spreading 55 members integral with the leaf and spaced apart to space the passageways apart, the said retarding and spreading members being staggered and being approximately of almond shape, the said bosses retarding the flow of the lubricating oil in the passageways and spreading the said lubricating oil widthwise between the contacting faces of adjacent leaves.

HOLDEN RIGBY.
